CAR CONSTRUCTION.

1,017,243.

Specification of Letters Patent. Patented Feb. 13, 1912.

Application filed August 20, 1907. Serial No. 389,325.

To all whom it may concern:

Be it known that I, EDWARD G. BUDD, a citizen of the United States, residing at Philadelphia, in the county of Philadelphia and State of Pennsylvania, have invented 5 certain Improvements in Car Construction, of which the following is a specification.

This invention relates to the construction of railway cars, especially those constructed 10 largely of metal so as to be practically fire-proof.

More particularly, the invention relates to 15 a metallic sheathing for either or both the interior and exterior surfaces of the side walls of a car.

The object of the invention is to provide 20 a metallic sheathing for various uses, as for instance in sheathing the side walls of cars, which consists of a plurality of similar sections, so that if one or more become damaged 25 in any way, they can be readily withdrawn and new ones substituted, which is made of pressed sheet-metal sections capable of manufacture at comparatively small cost, in 30 which the sections interlock so as to hold each other in proper relative position, and which presents an attractive appearance.

The sheathing constructed in accordance 35 with the invention is of great utility as a lining for the interior and exterior of the side walls of cars, the truss-work for the side walls and for supporting the roof lying between the two sheathings. As thus used, the sheathings form a double metallic wall permitting 40 comparatively little radiation of heat and affording spaces for packing heat-insulating material, if desired, and as the several sections are sprung in place and fit tightly together, vibration is reduced to a

The sections of the sheathing consist of 45 strips of sheet-metal pressed to provide on each section a body-portion and edge portions at the lateral edges of the body-portion turned at an angle thereto. In pressing the strips into form, these edge portions are provided with corresponding tongues and grooves. When the several sections are assembled, the tongue at one of the edges of each section 50 enters the groove at the edge of the adjacent section to position the sections relatively and the body-portions of the sections lie in substantially the same plane to form a

substantially unbroken wall. Preferably, the sections are so held that they are bowed 55 slightly and, being flexed thus, vibration is, to a very large extent, prevented.

The preferred embodiment of the invention is illustrated in the accompanying drawings in which—

Figures 1 and 2 are sectional views through the side wall of a car, Fig. 3 is an elevation of a portion of such wall, and Fig. 4 is a section through a length of the sheathing.

Referring to these drawings, 1, 2, 3 and 4 indicate sections of the sheathing, each formed of a strip of sheet-metal, preferably steel, pressed to provide a body-portion 5 and edge portions 6 and 7 at the lateral 70 edges thereof turned at an angle of ninety degrees to the body-portion 5. At the extreme edges of the strips, flanges 8 may be provided as shown. In pressing the sections into form, a rounded groove 9 is formed in 75 one of the edge portions, preferably at about the center thereof, and in the other edge portion a corresponding bead or tongue 10 is formed, these tongues and grooves extending throughout the length of the edge portions. 80 The sections thus constructed are assembled edge to edge as shown in Fig. 4 with the tongue 10 on each section entering the groove 9 in the adjacent section, and when thus positioned, the body-portions 5 of the 85 several sections lie in the same plane forming an unbroken wall except for the slight depressions at the joints between the sections which extend across the sheathing in parallel lines as shown in Fig. 3.

Figs. 1, 2 and 3 show the sheathing as applied to the interior and exterior of the side wall of a car, Fig. 1 being a section between two windows and Fig. 2 being a section through a window. The car itself may be of the usual or any suitable construction and is provided on the outer side thereof at the top and bottom with metallic pieces 11 and 12 of channel section running lengthwise of the car. The ends of the sections of the sheathing 13 enter these channels and are held in position thereby. The truss-work 14 of the side of the car has a strip 15 secured thereto and running lengthwise of the car and this strip is of such width that it bows the sections of the sheathing outwardly a

small amount, that is, it causes the sections of sheathing to be bent out of line somewhat so that they are curved in the direction of their length on an arc of very large radius, 5 this curvature being sufficient to flex the sections so that they will not be subject to vibration. On the inner side of the truss-work 14, a similar sheathing 16 is provided, this being held in position by suitable metallic strips of angular cross-section. Fig. 10 2 shows a window and its sash in section, 17 and 18 indicating the bottom or coping plates of the sash. The outer sheathing 13 is held at its lower end by the piece 12 and 15 at its upper end by the plate 18. Preferably, the outer edge of plate 18 extends downwardly a considerable distance and the sections of the sheathing are of such length that their upper ends may be inserted under 20 the edge of plate 18 and the sections then lowered to carry their lower ends into the trough of the piece 12, the upper ends of the sections being still held by the plate 18. The strip 15 puts these sections under flexure 25 by bowing them out slightly. The inner sheathing 16 is held in position by the plate 17 and an angle piece 19 secured to the floor of the car.

It will thus be seen that the side wall of 30 the car consists of two walls of metal, one or both of these being under spring tension so as to prevent vibration, the two walls limiting very much the radiation of heat, and the complete structure being fireproof.

35 The interlocking of the sections of the sheathing holds them against relative movement and the integral edge portions of the sheathing strengthen the body portions to resist damage thereto; if any portion of the

40 sheathing should become damaged, the sections thereof may readily be withdrawn and new ones substituted. The sections being of pressed sheet metal, may be manufactured at comparatively small cost and, though 45 comparatively thin, possess ample strength. The sections are so shaped as to provide insulating chambers therein which, either when they contain only air or when packed with heat-non-conducting material, reduce

50 the transmission of heat through the wall of the car so that the temperature within a car having the sheathing applied thereto will be higher in winter and lower in summer than that in cars as heretofore constructed.

Having described my invention, what I claim as new therein and desire to secure by Letters Patent of the United States is:

1. A metallic sheathing comprising a plurality of assembled sections of thin sheet-metal each having a body portion and the body portions of the several sections lying in substantially the same plane to form a wall, certain of said sections each having 60 integral edge portions at the lateral edges 65

thereof turned at an angle and so formed as to interlock a section with the sections adjacent thereto to hold it in position, and certain of said sections being removable from the sheathing independently of the parts adjacent thereto by a movement of the section away from said wall, substantially as described. 70

2. A metallic sheathing comprising a plurality of sections, certain of said sections consisting of sheet-metal strips pressed to provide a body-portion and integral edge portions at the lateral edges of the body-portion turned at an angle thereto, said sections being assembled with said body-portions lying in substantially the same plane, and means for subjecting said sections to flexure, substantially as described. 75

3. A metallic sheathing comprising a plurality of sections, certain of said sections consisting of sheet-metal strips pressed to provide a body-portion and integral edge portions at the lateral edges of the body-portion turned at an angle thereto and to form interlocking parts in said edge portions for positioning the sections, said sections being assembled with said body-portions lying in substantially the same plane and being removable one independently of the sections adjacent thereto by a movement 80 of the edge portions of the section toward each other to cause disengagement of the interlocking parts thereof, substantially as described. 85

4. A metallic sheathing comprising a plurality of sections consisting of sheet-metal strips pressed to provide in each a body-portion and integral edge portions at the lateral edges of the body-portion turned at an angle thereto and to form parts in said 100 edge portions for interlocking adjacent sections together, said sections being assembled with said body-portions forming a substantially unbroken wall, and means for bowing the sections in the direction of their length, 105 substantially as described. 110

5. A metallic sheathing comprising a plurality of sections consisting of sheet-metal strips pressed to provide in each a body-portion and integral edge portions at the 115 lateral edges of the body-portion turned at an angle thereto and to form parts in said edge portions for interlocking adjacent sections together, said sections being assembled with said body-portions forming a substantially unbroken wall, said edge portions extending at an angle to the wall to brace the same and having said parts interlocked to position the sections, and said interlocking parts being so formed that one section may 120 be inserted or removed by a movement toward or away from said wall, substantially as described. 125

6. In a car, a floor, supports for a side wall mounted thereon, a strip of angular 130

cross-section secured to the floor, a plurality of sheathing sections of sheet-metal each pressed to provide a body-portion and integral edge portions at the lateral edges thereof turned at an angle thereto, said sections being assembled on one side of said supports with their lower ends positioned by said strip and the body-portions thereof forming a substantially unbroken wall, substantially as described.

7. In a car, a floor, supports for a side wall mounted thereon, a strip of angular cross-section, secured to the floor, a plurality of sheathing sections of sheet-metal each 15 pressed to provide a body-portion and integral edge portions at the lateral edges thereof turned at an angle thereto, said sections being assembled on one side of said supports with their lower ends positioned 20 by said strip and the body-portions thereof forming a substantially unbroken wall, and a strip secured to said supports lengthwise of the car and coacting with said sections to bow the same in the direction of their 25 length, substantially as described.

8. A metallic sheathing comprising a plurality of assembled sections of thin sheet-metal each having a plane portion and the plane portions of the several sections lying 30 in substantially the same plane, certain of said sections having integral edge portions at the lateral edges thereof turned at an angle thereto and so formed as to interlock a section with the adjacent sections to position 35 the sections relatively, and separate devices coacting with the ends of said sections for holding them in position, substantially as described.

9. A metallic sheathing comprising a plurality of assembled sections of thin sheet-metal, certain of said sections having edge portions disposed at an angle to the body portions thereof to provide insulating chambers within the sections, and the edge 40 portions of said sections being adapted to yield toward each other when inserting a section and being formed to interlock one section with the sections adjacent thereto to position 45 them relatively, and a member of angular cross-section extending transverse to the sec-

tions and coacting with the ends thereof, substantially as described.

10. A metallic sheathing consisting of a plurality of assembled sections of sheet-metal, certain of said sections being provided 55 with a body-portion and with integral edge portions which interlock to position the sections relatively to the sections adjacent thereto with said body portions forming a wall and said edge portions being adapted to yield 60 toward each other when inserting the section in position, and a member extending transverse to the sections and coacting with the ends thereof, substantially as described.

11. A sheathing comprising a plurality of 65 sections of sheet-metal disconnected one from another and removable one independently of the sections adjacent thereto, each of said sections consisting of a sheet-metal strip pressed to provide a body-portion and integral edge portions at the edges thereof and turned at an angle thereto whereby insulating 70 chambers are formed within the sections, and said sections being assembled edge to edge with the body-portions thereof forming 75 a substantially unbroken wall, and a member extending transverse to the sections and coacting with the ends thereof, substantially as described.

12. A metallic sheathing comprising a 80 plurality of assembled sections of sheet-metal each pressed to form integral edge portions turned at an angle to the body-portions thereof to provide insulating chambers within the sections, the edge portions of 85 the sections being formed to interlock with each other to position the sections relatively with the body-portions thereof forming an unbroken wall and to permit removal of a section by a movement thereof away from 90 said wall, said edge portions being adapted to move toward each other to cause disengagement of said interlocking parts, substantially as described.

This specification signed and witnessed 95 this 9th day of August, 1907.
